UNITED STATES PATENT OFFICE.

HENRY C. TRAUT, OF MONMOUTH BEACH, NEW JERSEY, ASSIGNOR TO THE DIAMOND MATCH COMPANY, OF CHICAGO, ILLINOIS, A CORPORATION OF ILLINOIS.

MATCH CASE.

Application filed April 30, 1925. Serial No. 26,846.

To all whom it may concern:

Be it known that I, HENRY C. TRAUT, a citizen of the United States, and resident of Monmouth Beach, in the county of Monmouth and State of New Jersey, have invented certain new and useful Improvements in Match Cases, of which the following is a specification.

This invention has reference to cases for 10 match packets and particularly the type of case wherein the main body is provided with a hinged lid spaced from one end of the body to provide a transverse opening through which the ignition composition of 15 the confined match packet is exposed.

The object of my invention is to provide a case of the type referred to with a supplemental lid adapted to cover the said opening and protect the ignition composition of the 20 contained packet from exposure to dampness, etc., which supplemental lid is mounted and arranged in a simple and effective manner in relation to the main lid so that the latter, while it is being closed after the removal 25 of a match from the confined packet, automatically opens the supplemental lid to expose the ignition material and permit the striking of the head of the match thereon, which supplemental lid may thereafter be 30 manually closed; as will be hereinafter described and claimed.

In the drawings—

Figure 1 is a perspective view of a closed match case embodying my invention.

Fig. 2 is a similar view, showing the main lid swung open to expose the matches of the contained packet.

Fig. 3 is a similar view showing the main lid closed and the supplemental lid as 40 opened thereby to expose the ignition surface of the packet.

Fig. 4 is a section, enlarged, of the lower end of the packet, showing the supplemental lid and the adjacent hinged portion of the 45 main lid.

Fig. 5 is a transverse section, on the line 5—5 of Fig. 4.

Referring to the drawings, 6 designates the shallow body portion of the case, which 50 portion is usually tapering in form to accommodate a match packet including superposed rows of matches 7 having at their rear ends a connecting portion provided with an exterior coating 8 of prepared ignition composition. A lid 9 is hinged to the body 6 at 55

a suitable distance above the lower or narrow end of the latter by means of a cross-pin 10 supported in the side walls of the body, which pin passes through rolled or tubular portions 11 formed on the lower edge of the 60 lid. This lid is adapted partially to close the open side of the body 6 and confine the contained match packet, except the striking surface 8 of the latter. The ends of the body comprise curved walls 12, 13, respectively, which are bent up from the bottom, and the free end of the lid is curved to present a flange 14 adapted to overlap and closely hug the larger end wall 12 when the lid is closed. The wall 12 and flange 14 70 have an interlocking seat and a depression 15, 16, respectively, and the flange is also provided with a projection 17 to facilitate the opening of the lid.

According to my invention a supplemental 75 lid 18 of novel construction and operation is hinged to the body 6 coaxially with the main lid, in a manner to cover the adjacent open portion of the body and thus enclose and protect the ignition surface 8 of the confined 80 match packet. The lid is provided with an extended rolled or tubular portion 19 which is fitted between the tubular portions 11 of the main lid and in close relation to the adjacent edge 20 of the latter. The tubular 85 portion 19 receives the cross-pin 10 upon which the main lid is hingedly mounted, and hence the two lids are independently movable relatively to each other, excepting as hereinafter explained. The free end of 90 the supplemental lid 18 is curved to provide a flange 21 which overlaps the narrow end wall 13 of the case, and which flange is provided with one or more resilient lips 22 adapted to grasp the wall 13 when the lid 18 95 is closed and thus tend to hold such lid in closed position.

The tubular portion 19 of the lid 18 is slightly expanded to present an eccentric bearing surface 23 adjacent the body of the supplemental lid, so that when the main lid is swung open as indicated in Figs. 2 and 4, its edge portion 20 bears upon the surface 23 and becomes wedged thereon so tightly that when the main lid is being swung back to closing position (after, say, the removal of a match) the supplemental lid is forcibly pulled from the narrow end of the case and raised to the open position illustrated in Fig. 3, and by the dotted lines in Fig. 4. 110

When the main lid 9 is closed the match may be struck on the exposed ignition surface 8, whereupon the supplemental lid 18 can be forcibly closed in opposition to the wedge ¹⁵ connection and in locking relation to the narrow end of the case, and this without liability of releasing the lock of the main lid.

I claim—

10 A match case of the type described comprising a body portion and two independent lids therefor having co-axial hinge portions between the ends of the body portion, the free ends of said lids having fastening

means to engage the opposite ends, respectively, of the case, the hinge portion of one of said lids having a bearing portion with which the opposing edge of the other lid forcibly engages and binds when the latter is swung open, so that when the second-named lid is being closed it forcibly swings open the other lid. ²⁰

Signed at New York, in the county and State of New York this 28th day of April A. D. 1925.

HENRY C. TRAUTE.
